US00D831749S

(12) **United States Design Patent** (10) **Patent No.:** **US D831,749 S**
(45) **Date of Patent:** **** Oct. 23, 2018**

(54) **HANGING TENT STRUCTURE**

(71) Applicants: **Ricardo Bottome**, Boulder, CO (US);
Michael Cecot-Scherer, Louisville, CO (US)

(72) Inventors: **Ricardo Bottome**, Boulder, CO (US);
Michael Cecot-Scherer, Louisville, CO (US)

(73) Assignee: **Canaima Outdoors, Inc.**, Boulder, CO (US)

(**) Term: **15 Years**

(21) Appl. No.: **35/001,414**

(22) Filed: **Aug. 8, 2017**

(80) **Hague Agreement Data**

Int. Filing Date: **Aug. 8, 2017**

Int. Reg. No.: **DM/098022**

Int. Reg. Date: **Aug. 8, 2017**

Int. Reg. Pub. Date: **Oct. 27, 2017**
